BABY UNDERGARMENT

Irene R. King, Springfield, Mass.

Application September 15, 1950, Serial No. 185,114

2 Claims. (Cl. 2—111)

1

This invention relates to baby garments, and more particularly to an undergarment for an infant requiring diapers.

An object of this invention is to provide an improved garment for infants requiring diapers in which the securing of the diaper to the garment is effected without injuring the body of the garment and in a manner to materially enhance the comfort of the infant.

Another object of this invention is to provide an improved garment for an infant requiring diapers which is provided with means for the passage therethrough of the corners of the diaper to be secured, whereby the securing elements for the diaper do not pass through the body of the garment.

A further object of this invention is to provide an improved garment for an infant requiring diapers in which the securing of the diaper to the garment may be effected with smaller securing elements.

A still further object of this invention is to provide an undergarment for an infant requiring diapers which is relatively simple in structure and cheap to manufacture.

The above and still further objects and advantages of the invention will become apparent upon consideration of the following detailed description of the invention, when taken in conjunction with the accompanying drawings, wherein:

Figure 1 is a perspective view of the baby garment of the present invention shown on a baby and secured to a diaper without injury to the body of the garment and in a manner to materially enhance the comfort of the baby;

Figure 2 is a front elevational view of the baby garment of the present invention;

Figure 3 is an enlarged fragmentary elevational view showing the side portion of the baby garment illustrated in Figures 1 and 2; and

Figure 4 is an enlarged fragmentary sectional view taken along the line 4—4 of Figure 2.

Referring now more particularly to the drawings, wherein like reference numerals have been used throughout the several views to designate like parts, there is shown the baby garment of the present invention, generally designated by the reference numeral 10, which includes a garment body 11 having a neck opening 12 and spaced shoulder openings 13 and 14 cooperating to form the shoulder straps 15 and 16. The garment body has an open bottom 17 so that the garment 10 can be extended over the head and shoulders of the child, Figure 1, into a position

2

surrounding the upper portion of the child's body.

On each side of the garment body contiguous to and spaced from the open bottom 17 thereof there is provided a pair of transversely spaced, longitudinally extending slots, designated by the reference numerals 18 and 19, and 20, 21. The slots 18 to 21, inclusive, are for the passage therethrough of the corners of a diaper to be fastened together. As clearly shown in Figure 1, a diaper 30 is shown surrounding the lower portion of the body of the child and having the corners 31, 32 extended through the slots 18, 19 and 20, 21, inclusive, and detachably secured together by means of the safety pin 33. This manner of securing requires a smaller safety pin, since the safety pin does not have to be extended through the adjacent portions of the garment to thereby effect the securing of the diaper 30 to the garment 10. Further, holes will not be punched in the garment body 11, since the safety pin is not engaged with the body.

Circumposed about each slot of each pair and secured to the adjacent portions of the garment body 11 are the reinforcing structures 23 and 24. Each of the reinforcing structures is fabricated of a relatively strong and durable cotton-containing material and is secured in abutting relation with respect to the adjacent portions of the garment body 11 by means of the stitching 25 and 26. Each of the reinforcing structures 23 and 24 is provided with a pair of longitudinally extending, transversely spaced slots disposed in alignment with respect to the slots 18 to 21, inclusive. Engaged about the bounding wall of each slot of each pair and secured to the adjacent portions of the garment body and reinforcing structures 23 and 24 is the binding, generally designated by the reference numeral 27. The binding 27 may be in the form of buttonhole stitching which assures the firm securing of the bounding portions of the apertures provided in the body 11 to the bounding portions of the apertures provided in the reinforcing structures 23 and 24.

In actual use, the garment 10 is assembled about the body of the child, as shown in Figure 1, whereupon the free ends of the diaper 30 can be extended through the adjacent pair of slots. The securing of the corners, such as the corners 31, 32, can be effected by means of the safety pin 33 without injury to the body 11 of the garment 10, and in a manner to materially enhance the comfort of the infant.

Although only one embodiment of the garment

of the present invention has been described, it is readily apparent that numerous modifications can be made without departing from the spirit of the invention as set forth in the appended claims.

What I claim is:

1. In a baby garment for covering the body of a baby above the waist and having a neck opening in the upper end and spaced shoulder openings cooperating to form shoulder straps and having the lower end open, the improvement consisting of a pair of transversely spaced longitudinally extending slots formed in each side of said garment contiguous to and spaced from said open bottom for the passage therethrough of the corners of a diaper to be fastened together whereby said corners may be secured together separately of said baby garment, reinforcing means circumscribed about each of said slots of each pair and secured to the adjacent portions of said garment body, said reinforcing means each including a piece of cotton-containing material secured in confronting and abutting relation with respect to said adjacent portions of said garment body and provided with a pair of slots registering with said first-named pair of slots, and binding means engaged about the bounding walls of each pair of registering slots and secured thereto.

2. In a baby garment for covering the body of a baby above the waist and having a neck opening in the upper end and spaced shoulder openings cooperating to form shoulder straps and having the lower end open, the improvement consisting of a pair of transversely spaced longi-

tudinally extending slots formed in each side of said garment contiguous to and spaced from said open bottom for the passage therethrough of the corners of a diaper to be fastened together, whereby said corners may be secured together separately of said baby garment, reinforcing means circumscribed about each of said slots of each pair and secured to the adjacent portions of said garment body, said reinforcing means each including a piece of cotton-containing material secured in confronting and abutting relation with respect to said adjacent portions of said garment body and provided with a pair of slots registering with said first-named pair of slots, and binding means engaged about the bounding walls of each pair of registering slots and secured thereto.
